[57] CLAIM

[21] Appl. No.: 61,413

The ornamental design for a stabilizing base for a vehicle theft protection pedal lock, as shown and described.

[22] Filed: Oct. 23, 1996

DESCRIPTION

[51] LOC (6) CL 08-07

FIG. 1 is a stabilizing base for a vehicle theft prevention pedal lock showing my new design, the broken-line disclosure of a lock being for illustrative purposes only and forming no part of the claimed design;

[52] U.S. Cl. D8/343

FIG. 2 is a front view thereof;

[58] Field of Search D8/330, 331, 343;

FIG. 3 is a left side view thereof, the right side being identical;

70/14, 19, 51, 54, 55, 56, 57, 158, 431.

FIG. 4 is a top view thereof; and,

DIG. 43

FIG. 5 is a bottom view thereof.
